UNITED STATES PATENT OFFICE.

ANTON J. ANDERSON, OF BROOKLYN, NEW YORK.

COMBINED HOLDING AND MOUNTING DEVICE FOR MAINSPRINGS.

Application filed May 5, 1924. Serial No. 711,093.

To all whom it may concern:

Be it known that I, ANTON J. ANDERSON, a subject of the King of Sweden, and a resident of the city of New York, borough 5 of Brooklyn, in the county of Kings and State of New York, have invented a new and Improved Combined Holding and Mounting Device for Mainsprings, of which the following is a full, clear, and exact description.

This invention relates to improvements in combined holding and mounting devices for mainsprings for watches and is designed especially as an improvement over 15 my co-pending application, Serial No. 649, 324, filed July 3rd, 1923.

In said co-pending application the holder is formed from a flat piece of material having an opening therein in which the main- 20 spring is mounted and said opening communicating with a slot through which the free end of the spring projects in spaced relation to the material of the holder forming an adjacent edge of said slot. This construction permits of the free end of the 25 spring being attached to the barrel in which the spring is to be mounted by flexing said free end transversely with respect to the remainder of the spring so that said free end 30 may be disposed beneath the adjacent portion of the holder and thereafter attached to the barrel when the holder is placed upon the barrel preparatory to inserting the entire spring into the barrel. However, in 35 thus mounting the spring the free end thereof must be flexed transversely to a considerable extent so as to permit of its being positioned beneath the holder previous to the attachment of said end in the barrel and the 40 insertion of the entire spring into said barrel. Care must, therefore, be exercised to prevent excessive flexing of the spring for if a sufficient amount of the outer convolution of the spring is projected beyond the 45 edge of the opening in the holder the expandable pressure of the spring might result in its accidental detachment from the holder.

It is, therefore, an object of the present invention to avoid the possibility of accidental detachment of the spring from the 50 holder when mounting the spring and to this end the holder is so constructed that the spring may be inserted into the barrel

with only a very slight transverse flexing 55 of the free end of the spring.

The above and other objects will appear more clearly from the following detailed description, when taken in connection with the accompanying drawing, which illustrates a preferred embodiment of the inventive idea. 60

In the drawing—

Figure 1 is a plan view of the holder constructed in accordance with the invention and showing the mainspring mounted there- 65 in;

Figure 2 is an edge elevation; and

Figure 3 is a perspective view, partly broken away and shown in section, illustrating the manner of mounting the spring in a barrel and showing the position of the parts 70 just previous to the insertion of the entire spring into said barrel.

Referring more particularly to the drawing, the numeral 4 indicates a barrel of known construction forming the part of the 75 mechanism of a timepiece in which the main-spring 5 is designed to be mounted. The inner wall of the barrel is provided with a projection (not shown) usually found in barrels in which the type of spring shown in the drawing is designed to be mounted, said spring having an opening 6 in its free 80 extremity capable of receiving the projection when said extremity is being attached in the barrel. It will, of course, be understood that other types of springs, such as that illustrated in the above-mentioned co-pending application, may be mounted in barrels with equal facility.

The holding and mounting device, which 90 comprises the essential features of the invention and which is utilized to maintain the spring in coiled position after the same has been placed upon the market, consists of a body 7 formed of a substantially flat crescent- 95 shaped plate made of any suitable material, such as aluminum. The body is provided with an eccentrically disposed opening 8 of a diameter less than that of the open end of the barrel 4 so that when the device 100 is employed for mounting the spring in the barrel the body may be rested upon the peripheral edge of the open end of said barrel with the opening 8 disposed substantially concentric to said open end. The material 105 of the body between the outer edge thereof

and the edge of the opening 8 is of greater width than the thickness of the body and at the point of least width of said material the body is further provided with a slot 9 communicating with the opening 8. By forming the opening 8 eccentrically, as shown, the body has its greatest width at a point diametrically opposite the slot 9. This increase in width over the end portions of the body imparts greater strength and rigidity thereto than if the opening were formed centrally and hence enables the device to better withstand the expansive pressure of the coil spring which has a tendency to force the ends of the device apart.

The spring 5 is first coiled and then placed within the opening 8 and allowed to expand until the outer convolution thereof engages the edge of the opening with said edge in contact with said outer convolution at a point intermediate the edges of the latter. The free extremity of the spring is permitted to project outwardly through one end of the slot 9, as shown in Figure 1, and out of contact with the material forming the opposite edge of said slot. By making the width of the body between the opening and the outer edge thereof relatively great as compared to the thickness of said body, it will be obvious that the material between said opening and the outer edge of the body forms effective gripping surfaces by means of which the device may be readily handled when applying the same in position on the barrel and mounting the spring in place.

Preparatory to mounting the spring in the barrel it is desirable, though not necessary, to move the spring laterally in its opening 8 until one edge thereof is practically flush with the upper surface of the body, as indicated in Figure 3. The free extremity of the spring is then flexed transversely relative to the remaining portion thereof a very slight degree sufficient to enable said extremity to be inserted into the barrel and its opening engaged over the projection on the inner wall of said barrel. During this attaching operation the body may be rested upon the edge of the open end of the barrel, or in close proximity thereto and after said free extremity is attached it is necessary to manipulate the holder so as to flex said extremity inwardly toward the adjacent convolution of the spring so that said free extremity will conform generally to the contour of said convolution. In my co-pending application, mentioned above, this inward flexing of the spring is accomplished previous to the attachment of the free extremity in the barrel, necessitating considerable transverse flexing of the spring to engage the free extremity with the under surface of the body. In the present construction means are provided which will enable the

free extremity of the spring to be deflected to a position beneath the body, and consequently in a position where said free extremity will conform to the contour of the adjacent convolution, by a manipulation of the holder without in any way handling the spring. This is accomplished by bending the material of the body at the ends thereof adjacent the slot 9 to form the upstruck portions 10 which project beyond the upper edge of the spring 5, even when the spring is mounted as shown in Figure 2. Depending upon the position in which the spring is mounted in the body one of the bent or upstruck portions 10 will be adjacent to the free extremity of the spring and will present an inclined surface thereto which will be engaged by the upper edge of the spring, as above mentioned. Thus after the free extremity of the spring has been attached in the holder a pressure is exerted upon the latter transverse to the plane of the peripheral edge of the barrel and toward the point of attachment of the spring with the barrel. This pressure results in the inward flexing of the spring and its engagement with the under inclined surface of the adjacent bent portion 10 until the portion of the spring extending below the holder is entirely disposed within the barrel. A slight inward pressure upon the spring itself will then project said spring entirely from the holder and into the barrel where the same expands into proper position.

What is claimed is:

1. In a combined holding and mounting device for mainsprings, a body capable of being placed upon a barrel in which the spring is to be mounted and having an opening for receiving said spring, and a slot communicating with said opening through one end of which one extremity of said spring is extended, said body having means adjacent said slot and said extremity of the spring capable of being engaged by said extremity to deflect the same to a position under the body when the latter is manipulated relative to the barrel to project said spring into the barrel.

2. In a combined holding and mounting device for mainsprings, a body having an opening therein for receiving a coiled spring, and a slot communicating with said opening and through one end of which one extremity of said spring is extended in spaced relation to the material forming the other end of said slot, the material of said body being formed with an inclined surface capable of being engaged by said extremity of the spring to force the latter into engagement with the under surface of said body after said extremity has been attached to a barrel.

3. In a combined holding and mounting device for mainsprings, a body formed of a sheet of material having an opening therein

for receiving a coiled spring, and a slot communicating with said opening through which one extremity of said spring projects in spaced relation to the adjacent edge of said body, the portion of said body adjacent said free extremity being bent to form a surface inclined with respect to the remaining por-

tion of said body and said surface being disposed in the path of movement of said free extremity when the latter is flexed inwardly ¹⁰ toward the adjacent convolution of said spring.

ANTON J. ANDERSON.
